UNITED STATES PATENT OFFICE.

CLAES A. SVENSSON, OF BUFFALO, NEW YORK.

WIRE-GRIP.

977,236.

Specification of Letters Patent. Patented Nov. 29, 1910.

Application filed March 18, 1910. Serial No. 550,173.

To all whom it may concern:

Be it known that I, CLAES A. SVENSSON, a citizen of the United States, residing at Buffalo, in the county of Erie and State of New York, have invented new and useful Improvements in Wire-Grips, of which the following is a specification.

This invention relates to grips designed more particularly for use by linemen for 10 grasping telephone and telegraph wires while stringing or tightening the same. A grip of this character is shown and described in Letters Patent of the United States No. 496,104, granted to myself April 25, 1893. 15 These grips have usually been provided with a spring which operated constantly to close the jaws of the grip. This necessitated holding the jaws apart by hand in opposition to the resilience of the spring preparatory to 20 applying the jaws to the wire to be gripped. Inasmuch as the lineman is often in a position which permits him to use but one hand for manipulating the grip, for instance, when holding himself by the other hand on a pole, 25 it is then a difficult matter for the lineman to both hold the jaws open against the spring pressure and also apply the same to the wire to be grasped.

It is the object of this invention to provide 30 a simple, efficient and durable retaining device for the grip, whereby the jaws of the same may be held in an open position against the action of the spring without using the hand for this purpose, thereby leaving the 35 latter free to apply the grip easily and conveniently to the wire and whereby the jaws after being applied to the wire may be quickly and easily released so as to permit the same to grasp the wire.

40 In the accompanying drawings: Figure 1 is a side elevation of a grip provided with one form of my retaining device and showing the same in an open position. Fig. 2 is a similar view, partly broken away, and showing 45 the position of the parts when the jaws are closed. Fig. 3 is an edge view thereof corresponding to Fig. 2. Fig. 4 is a cross section in line 4—4, Fig. 1. Fig. 5 is a plan view of a grip showing another form of my invention. Fig. 6 is a sectional top plan view of a grip showing another form of my invention. Fig. 7 is a sectional top plan view of a grip showing still another form of my invention. Fig. 8 is a fragmentary longitudinal

section in line 8—8, Fig. 7. Fig. 9 is a sectional top plan view of a grip showing another form of my invention.

Similar letters of reference indicate corresponding parts throughout the several views.

Referring to Figs. 1—4, A represents the body or main member of the grip which has the form of a longitudinal bar. The front part *a* of this body forms the stationary jaw of the grip. B is the movable jaw which is arranged opposite the stationary jaw and movable toward and from the latter for closing and opening the grip. For this purpose the stationary and movable jaws are preferably pivotally connected at their ends by a link C and pivotally at their front ends by the inner arm *d* of an actuating lever D, so that the jaws always remain parallel. E is a draft loop or member movable lengthwise on the rear end of the body bar and F the two sections or members of a coupling link connecting the outer arm *d* of the actuating lever with the loop so as to transmit the movement of the latter to the lever. The rear ends of the coupling link sections F are arranged on opposite sides of the body A and the ends or arms *e*, *e*¹ of the draft link are arranged on the outer side of the link sections F. This draft loop and the coupling link sections are pivotally connected by a transverse pin *g* which passes through a longitudinal slot *h* in the rear part of the body A. I represents a spring which tends constantly to move or press the two jaws toward each other and close the grip. This spring is preferably arranged between the members of the coupling link F and engages at one end with a shoulder or pin *i* on one member of this link while its other end engages with a shoulder *i*¹ on the adjacent outer end of the actuating lever.

Heretofore a lineman, when applying this grip to a wire I¹ had to hold the same open manually which at times was very difficult particularly when only one hand was free to manipulate the grip and the latter was provided with a spring which tended constantly to close the jaws of the grip. For holding the jaws in an open position without requiring the use of the hand for this purpose, a retaining device is provided which can be rendered inoperative after the jaws have been applied to the wire and thus permit the

latter to be grasped by the jaws. The means for this purpose shown in Figs. 1-4 are designed to perform this function frictionally and comprise a retaining, clamping or pressing finger J projecting from the branch or arm e of the loop E adjacent to the pin g and toward that side on which the coupling link F is arranged and having an inclined or cam-shaped underside, as shown at j.

- 10 Normally the jaws of the grip are closed and its loop is arranged parallel with the body. Preparatory to applying the grip to a wire the lineman first pushes the loop and rear end of the coupling link forwardly so as 15 to open or separate the jaws and also turns the loop laterally out of parallelism with the body so that the retaining finger is shifted from a position in rear of the coupling link, as shown in Fig. 2, to a position in which 20 the retaining finger is arranged above one of the members of the coupling link, as shown in Fig. 1. In thus moving the retaining finger over the coupling link its inclined underside engages the edge of the 25 link and the finger is deflected out of its normal position or strained so that when the same is arranged above the link it bears against the latter by its end and thus draws the two members or sections of the link F 30 against opposite sides of the body A, through the medium of the loop, thereby holding the parts of the grip frictionally in a position in which its jaws are open, as shown in Figs. 1 and 4. The grip may now be applied 35 freely and conveniently by one hand to a wire without being obliged at the same time to hold the jaws open by hand. After the jaws are applied to the wire it is only necessary to turn the loop from the laterally inclined position, shown in Fig. 1, to the position 40 in which it is in alignment with the body A, whereby the retaining finger is disengaged from the coupling link and the sections are disengaged from the body, whereby 45 the spring is free to shift the parts of the grip in a direction for closing the jaws against opposite sides of the wire, as shown in Fig. 2.

Instead of holding the jaws frictionally in 50 their open position this may be effected mechanically. Means of the last mentioned character are shown in Figs. 5, 6, 7, 8 and 9.

In the modification of my invention shown in Fig. 5, the jaws are held in an open position by turning the draft member E laterally when the same is in its foremost position and thereby cause a hook p on the draft member adjacent to its pivot to engage with a pin p¹ on the body A. Upon straightening out the draft member after the wire 55 has been placed between the jaws the hook p will clear the pin p¹ and permit the jaws to close on the wire.

The jaws, as shown in Fig. 6, may also be 60 held in an open position by providing the

guide slot h¹ of the body at its front end with an enlarged part h² and constructing the pivot pin of the draft member with an oblong central part g¹ and connecting this pivot with the draft member so as to turn 70 with the latter. When the draft member is in its rearward position the flat sides of the oblong part g¹ of the pivot pin engage with opposite sides of the narrow rear part h¹ of the slot, thereby holding the draft 75 member against turning but permitting the same to slide forwardly and backwardly on the body. Upon pushing the draft member forwardly until the oblong part of its pivot pin is in the enlarged part h² of the slot and 80 then turning the draft member laterally the oblong part will be arranged crosswise in the enlargement h² and at an angle to the straight part and prevented from entering the latter, thereby locking the jaws in an 85 open position, ready for receiving the wire. After the wire is placed between the jaws the draft member is straightened, so that the flat side of the oblong part g¹ is in line with the straight part of the slot when the draft 90 member may be moved backwardly and the jaws closed on the wire.

The form of detent device shown in Figs. 7 and 8 comprises a slot h³ arranged lengthwise in a body A and having an enlargement h⁴ at its rear end. Extending through this slot, through the coupling links F¹, F¹ arranged on opposite sides of the body and through the arms e², e³ of the draft member or loop E is a pivot bolt having a flat sided 100 central part q which is arranged in the slot, a cylindrical part q¹ on which one arm of the coupling links and one of the draft arms turn, a head or shoulder q² at one end bearing against the outer side of the adjacent 105 draft arm, and a screw thread q³ at its opposite end which engages with an internally threaded opening in the other draft arm. While the pivot bolt is in the enlarged rear part h⁴ of the slot the same may be connected with the arms of the draft loop and the coupling links and also adjusted relatively to these parts. Upon pushing the 110 draft loop forwardly, so that the central flat sided part q of the pivot bolt enters the straight part of the slot h³ this bolt cannot turn. By turning the draft loop laterally 115 while the same is in this forward position and the jaws are open the threaded lower arm of the loop tightens on the pivot bolt 120 like a screw nut and causes the coupling links to be drawn against opposite sides of the body A, thereby holding the jaws in an open position. Upon again straightening the draft loop the coupling links are released 125 from the body, thereby permitting the jaws to close.

In Fig. 9 is shown a detent device which operates to hold the jaws yieldingly in a closed or open position. The means for this 130

purpose consist of a spring I^1 mounted on one of the members of the link F^2 and bearing at one end against an abutment lug r on the adjacent outer end of the actuating lever D^1 . When the jaws are opened fully the spring I^1 bears against the lug r on one side of the dead center of the pivotal connection between the coupling link and the lever, as shown in Fig. 9, and holds the jaws yieldingly in this position. Upon moving the draft loop backwardly and closing the jaws sufficiently to cause the abutment lug to be shifted, so that the pressure of the spring I^1 against this lug is on the opposite side of the dead center of the pivotal connection between the coupling link and lever, the spring I^1 will then operate to hold the jaws yieldingly in a closed position.

It will be noted that in the several constructions shown and described, the draft member when moved into its abnormal position operates to hold the jaws open while upon moving the draft member into its normal position the jaws are permitted to close.

I claim as my invention:

1. A grip having a pair of jaws which are relatively movable for opening and closing the grip, a draft member operatively connected with said jaws and movable into and out of its normal position, and means for holding said jaws in an open position while the draft member is in its abnormal position and which permit said jaws to close upon moving the draft member into its normal position.

2. A grip having a body provided with a stationary jaw, a movable jaw coöperating with the stationary jaw, a lever pivotally connecting the jaws, a draft member slideable lengthwise on the body and movable laterally into its normal or abnormal position, a link connecting the draft member and lever, a spring for closing said jaws, and means which operate to hold said jaws in an open position when the draft member is in its abnormal position and which permit said jaws to close upon moving the draft member into its normal position.

3. A grip having a body provided with a stationary jaw, a movable jaw coöperating with the stationary jaw, a link connecting said jaws, a lever pivotally connecting the jaws, a draft member slideable lengthwise on the body and movable laterally into its normal or abnormal position, a link connecting the draft member and lever, a spring for closing said jaws, and means which operate to hold said jaws in an open position when the draft member is in its abnormal position and which permit said jaws to close

upon moving the draft member into its normal position.

4. A grip having a body provided with a stationary jaw, a movable jaw coöperating with the stationary jaw, a link pivotally connecting said jaws, a lever pivotally connecting said jaws, a draft member slideable lengthwise on the body, a link connecting the draft member with said lever, and means operated by said draft member for pressing said last-mentioned link against said body. 65

5. A grip having a body provided at its rear end with a longitudinal slot and a stationary jaw at its front end, a movable jaw coöperating with the stationary jaw, a link pivotally connecting said jaws, a lever pivotally connecting said jaws, a coupling link having two sections which are pivotally connected at their front ends with said lever and are arranged at their rear ends on opposite sides of said body, a draft loop having the front ends of its arms arranged on the outer side of said coupling link sections, a pin passing through said draft loop arms, said coupling link sections and the slot of said body, and a retaining finger arranged on one arm of the draft loop adjacent to said pin and having an inclined under side and adapted to engage with one of said coupling link sections. 90

6. A grip having a body provided at its rear end with a longitudinal slot and a stationary jaw at its front end, a movable jaw coöperating with the stationary jaw, a link pivotally connecting said jaws, a lever pivotally connecting said jaws, a coupling link having two sections which are pivotally connected at their front ends with said lever and are arranged at their rear ends on opposite sides of said body, a draft loop having the front ends of its arms arranged on the outer side of said coupling link sections, a pin passing through said draft loop arms and said coupling link sections on the slot of said body, a spring for moving said jaws into a closed position arranged between said coupling link sections and engaging at one end with one of said sections and at its opposite end against said lever, and a retaining finger arranged on one arm of the draft loop adjacent to said pin and having an inclined under side and adapted to engage with one of said coupling link sections. 100 105 110

Witness my hand this 17th day of March, 1910.
